UNITED STATES PATENT OFFICE.

ALEXANDER J. McDONOUGH, OF CHAUNCEY, PENNSYLVANIA.

POST-BASE.

1,101,307.

Specification of Letters Patent. Patented June 23, 1914.

Application filed June 13, 1912. Serial No. 373,493.

To all whom it may concern:

Be it known that I, ALEXANDER J. McDONOUGH, a citizen of the United States, residing at Chauncy, in the county of Luzerne and State of Pennsylvania, have invented new and useful Improvements in Post-Bases, of which the following is a specification.

The invention relates to post anchors, and more particularly to the class of adjustable post clamping bases.

The primary object of the invention is the provision of a base of this character wherein a post will be firmly held and fixed to the ground so as to sustain the same rigid in upright position for the fastening of a fence thereto.

Another object of the invention is the provision of a base of this character wherein different sizes of posts can be anchored in vertical position rigidly held fixed to the ground without requiring the sinking of the lower end of the post therein or the mounting of the same in a cementitious base.

A further object of the invention is the provision of a base which is extremely simple in construction, thoroughly reliable and efficient in its purpose, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawings:—Figure 1 is a perspective view of a base constructed in accordance with the invention, showing by dotted lines a portion of a post held therein. Fig. 2 is a sectional view on the line 2—2 of Fig. 1. Fig. 3 is a fragmentary vertical sectional view.

Similar reference characters indicate corresponding parts throughout the several views in the drawing.

Referring to the drawing by numerals, the base comprises superposed plates 5 and 6 respectively, which are of complementary shape, preferably square, and may be made from any desirable material, the same being united to or integral with a column or pedestal 7 which is arranged centrally thereof,

the uppermost plate 6 being formed with spaced parallel slots 8 opening through one edge thereof for a purpose presently described.

Supported upon the uppermost plate 6 is a post clamp comprising a split or two-part tubiform column 9, both parts of which are provided at their longitudinal edges with out-turned ears 10, the ears of one part being adapted for engagement with adjusting bolts 11 which are engaged therewith and are also passed through the ears on the other part of the column so that the said two parts of the column can be adjusted with relation to each other and for securely clamping a post 12 therein for vertically supporting the same, the said bolts carrying nuts 11' for securing the same in the ears. The lower end of the column 9 on both parts thereof is formed with out-turned wings forming feet 13 through one of which are passed permanent fasteners 14, while the other wing has passed therethrough adjustable bolt members 15, the same being engaged in the slots 8 and carrying the usual nuts 16 which work against the under face of the uppermost plate 6 so that one of the parts of the column 9 can be adjusted and fastened in such position with respect to the other part thereof which is permanently fixed to the plate 6 as shown.

In the mounting of the base the lowermost plate 5 and post 7 are embedded in the ground so that the uppermost plate 6 will lie substantially on a level with the surface of the ground or slightly beneath the same, and the post is clamped within the column 9 in a manner as hereinbefore described.

What is claimed is:

1. A post support comprising a base section formed with spaced parallel slots opening through the free edge thereof, a pair of semi-tubular shaped members arranged opposite each other and having out-turned lower ends superimposed upon the section, means permanently fastening one out-turned end to the section, and bolt members passed through the other out-turned end and adjustably engaged in the slots in the base section.

2. A post support comprising a base section formed with spaced parallel slots open-

ing through the free edge thereof, a pair of semi-tubular shaped members arranged opposite each other and having out-turned lower ends superimposed upon the section, 5 means permanently fastening one out-turned end to the section, bolt members passed through the other out-turned end and adjustably engaged in the slots in the base section, outwardly projecting ears formed 10 at opposite edges of the semi-tubular shaped

members, and bolt members passed through the said ears for the clamping of the said members about a post.

In testimony whereof I affix my signature in presence of two witnesses.

ALEXANDER J. McDONOUGH.
